UNITED STATES PATENT OFFICE

BERTRAND H. WAIT, OF NEW ROCHELLE, NEW YORK

PAVEMENT AND PROCESS OF CONSTRUCTING A PAVEMENT

Application filed September 27, 1927. Serial No. 222,354.

My invention relates to articles of manufacture made of concrete and particularly to pavements, platforms, floors and the like, or other structures having surfaces exposed to wear or deterioration and which, at sometime, it may be desirable to replace without the necessity of replacing the entire structure. It relates to improvements in the structure and the method of construction 5 disclosed in my United States Patent No. 1,628,482 whereby a monolith of concrete having a predetermined stratum of cleavage therein may be constructed.

In the aforesaid patent there is disclosed 15 a monolith of concrete having a stratum therein along which the monolith may be cleft or split, and formed by incorporating in the monolith a fabricated medium dividing the stratum into a multiplicity of comparatively small areas of integrity with the concrete on either side thereof. The preferred medium is a cloth or fabric of the general character of burlap or cheese cloth. Such a medium may be incorporated in the 20 concrete and may extend, in the case of a pavement or roadway, from edge to edge thereof.

In most instances such a form of construction will give very satisfactory results but 30 where considerable water or moisture is encountered, in connection with freezing temperatures, there is danger that moisture will penetrate into the cleavage stratum by capillary attraction along the threads of the fabric. When this moisture freezes, the expansive force developed may be sufficient to effect a partial separation of the monolith along the cleavage stratum. When the bond 35 has once been broken at the edge of the pavement, a greater space for the entrance of moisture is provided and the separating may progress across the slab.

In order to prevent this, I propose to 40 start the cleavage plane proper some distance in from the exposed edges of the monolith so that no portion of the fabric, which is more or less an absorbent of moisture, extends through to the exterior of the monolith. I also propose to provide, where 45 necessary or desirable, intermediate mois-

ture barriers or dams for preventing or obstructing the passage of water from one cleavage stratum to another.

The objects of my invention therefore, are to provide a monolithic concrete structure 55 having a predetermined stratum therein along which the monolith may be cleft or split, and in which the liability of moisture seeping into the cleavage stratum from points exterior of the monolith will be substantially eliminated. Another object is to provide a monolithic structure having a stratum therein along which the monolith may be generally cleft or split by suitable mechanical means but in which spaced 60 dams or barriers are provided to prevent the seepage of moisture from one section of the pavement to another. 65

With these objects in view my invention includes the novel structure and the method 70 of constructing the same which is described below and illustrated in a more or less typical manner in the accompanying drawings, in which—

Fig. 1 is a typical cross section of a monolithic pavement having a cleavage stratum therein with moisture barriers at the lateral edges; 75

Fig. 2 is a plan view of a monolithic slab showing a portion of the upper surface removed along the cleavage stratum; 80

Fig. 3 is an enlarged, fragmentary section normal to the cleavage stratum;

Fig. 4 illustrates an intermediate stage in the preferred type of construction; and 85

Fig. 5 illustrates an intermediate stage in a slightly modified type of construction.

Referring to the drawings, 1 generally represents a monolithic concrete structure having a lower course, 2, and an upper course, 3, and an intermediate medium, 4, of such a character that a direct bond between the upper and lower courses is provided through the medium but which will form a zone or stratum of comparative 90 weakness along which the monolith may be cleft or split. 95

In constructing a pavement or the like, the lower course, 2, is first laid upon a sub-grade or other foundation. According to 100

my preferred method of procedure, this bottom course is then worked or manipulated so that a thin layer of mortar, 5, is brought to the surface. Upon this surface is laid a fabricated medium, 4, which is pervious 5 to mortar but substantially impervious to coarse aggregate, and which, for reasons hereinafter mentioned, I prefer to embed slightly in the mortar, or at least to press slightly by a light roller or otherwise, so that mortar is forced therethrough. The extreme edges of the fabric are placed so that they will not project through the edges of the slab. In other words, the bottom course is not completely covered by the fabric, but a slight margin, 6, is left between the edges of the fabric and the exposed edges of the pavement. The upper course is then placed immediately and before the lower course has attained its initial set, and the surface is finished by the usual methods.

The medium which I propose to use may be of almost any character provided it will divide a stratum of the concrete into a multiplicity of spaced, comparatively small or minute areas, 10. For example, ordinary cheese cloth, which is cheap, gives very satisfactory results, and any fabric or fabricated medium such as metal screen, cloth, burlap or the like having comparatively small, closely spaced interstices which will permit an integral mortar bond between the concrete on either side thereof and yet give the desired cleavage may be employed. The interstices or perforations in the medium should be of such size that comparatively large portions of the coarse aggregate particles cannot project therethrough thus providing an interrupted stratum consisting substantially of mortar which is comparatively weak. In connection with the general character of the medium which I propose to employ, it is to be understood that the purpose of this invention is not to strengthen or reinforce the monolith but to render it susceptible to splitting along a predetermined surface or stratum without otherwise substantially affecting its strength. In other words, the medium which I propose to incorporate is of such character that it weakens rather than reinforces the concrete. Hence the structural strength of the medium itself is substantially immaterial and for economical reasons is preferably light in weight and of slight structural strength.

The width or extent of the margin, 6, depends somewhat upon the thickness of the top course and the character of the materials therein, and should be such that when the top course is being cleft from the bottom course, by mechanical means, the splitting action will "carry across" the margin. Inasmuch as the margin is merely to provide a dam or barrier which will prevent

seepage of moisture into or between the strands of the fabric, it may be made quite narrow, and generally speaking, its width should not exceed the thickness of the top course. In addition to leaving a margin along the exposed edges of the pavement, similar margins may be left at either side of the joints, 7, in the pavement. Likewise, transverse dams, 8, or longitudinal dams, 9, may be provided dividing the cleavage stratum into such sections as may seem desirable thus preventing the seepage of moisture from one section to another.

These intermediate dams may be formed by placing separate pieces of fabric upon the bottom course and leaving the desired spaces between to permit a full adhesion there of the top and bottom courses. Where such a procedure is objectionable, a specially woven fabric, such as that illustrated at 11, 80 may be employed. Here, the fabric is a continuous strip and comprises substantial areas, 12, in which the strands thereof are comparatively closely spaced, say $\frac{1}{8}$ " or $\frac{1}{4}$ ", and which said areas are connected by comparatively narrow portions, 13, in which the strands are rather widely spaced, say $\frac{1}{2}$ " or $\frac{3}{4}$ ". Throughout these narrow, coarsely woven portions the adhesion will be substantially 100% between the top and bottom courses and yet the total expansive force which may be developed by water freezing along the comparatively widely spaced strands will not be sufficient to effect a separation of the concrete.

As pointed out in my patent aforesaid, the interposition of the fabric does not lessen the beam support of the slab, and yet the concrete is readily cleavable along the plane of the fabric. When the monolith is cleft, the closely spaced, minute bonds of integrity, 10, between the courses, and which are formed by the mortar penetrating the interstices of the fabric, break separately, so that the splitting of the concrete is progressive across the stratum of cleavage. The actual area of the strands of fabric is only a small percentage of the total area in the plane of the fabric and the matrix contact between the upper and lower courses comprises a substantial percentage of the total area in the cleavage stratum. This matrix contact, however, is divided into a multiplicity of very small integral parts by the strands of the fabric, and these small parts 115 or sections break one by one when the monolith is cleft.

In constructing my pavement, it is to be understood that the method of procedure is in nowise limited to the working of the bottom course to produce a mortar surface thereon. The fabric may, if desired, be merely laid upon the lower course either with or without manipulation of that course, and it is not necessary to press the fabric 130

into the lower course as described in my preferred method of procedure. However, it will be obvious that by manipulating the bottom course so as to bring the mortar to the surface, and slightly embedding the fabric in this mortar, the cleavage stratum will be located in a zone of comparatively weak mortar or matrix so that separation of the monolith along this stratum will be facilitated. Furthermore, slightly embedding the fabric stiffens up the lower course so that the materials of the upper course will not be worked into the base, and the poorer materials of the lower course will not be worked up into the top course. In this way, the upper course can be built of a uniform consistency and depth, thus eliminating hair checking and initial cracking due to uneven depth and lack of uniform consistency. Again, the upper course may be quite thin and may be laid comparatively dry and of a rich mixture. Such a course requires very little manipulation and no poor materials will be worked to the top and cause scaling.

My pavement may, of course, be laid with expansion and contraction joints, with steel or other reinforcing where desired, and of any mixture or depth, all as required by the traffic, temperature variations, subgrade and other conditions affecting the design as a structure.

While I have described my invention in its preferred embodiment it is to be understood that the words which I have used are words of description rather than of limitation and that changes within the purview of the appended claims may be made without departing from the true scope and spirit of my invention in its broadest aspects.

What I claim is—

1. A monolithic concrete slab or the like having a stratum therein along which it may be cleft or split including zones divided into a multiplicity of spaced, comparatively small areas of integrity with the concrete on either side of said stratum and zones of substantially complete, uninterrupted integrity adapted to obstruct the passage of moisture between the first mentioned zones.

2. A monolithic concrete slab or the like having a stratum therein divided into a multiplicity of spaced, comparatively small areas of integrity with the concrete on either side of said stratum but terminating short of the edges of said slab, whereby seepage of moisture into said stratum is substantially prevented by the surrounding solid concrete.

3. A monolithic concrete slab or the like having a cleavage stratum distinguished in section by zones comprising a multiplicity of spaced, comparatively small area of concrete, separated by comparatively narrow zones of substantially continuous concrete.

4. A monolithic concrete slab or the like having a cleavage stratum therein distin-

guished in section by a zone comprising a multiplicity of spaced, comparatively small areas of concrete, and a contiguous zone of substantially continuous concrete.

5. A monolithic concrete slab or the like having a cleavage stratum distinguished in section by a zone comprising a multiplicity of spaced, comparatively small areas of concrete surrounded by a zone of substantially continuous concrete adapted to form a moisture barrier about first mentioned zone.

6. A monolithic concrete pavement or the like having a stratum therein along which the monolith may be cleft or split, and comprising a lower course, an upper course and an intermediate layer of slightly spaced pieces of fabric pervious to mortar but substantially impervious to coarse aggregate; the spacing between said pieces being sufficient to form a moisture barrier of solid concrete extending between the upper and lower courses but not sufficient to prevent a substantially continuous splitting of the monolith along the cleavage stratum.

7. A monolithic concrete pavement or the like comprising a lower course, an upper course, and an intermediate layer comprising a fabricated medium pervious to mortar but substantially impervious to coarse aggregate; said intermediate medium terminating slightly short of the exposed lateral edges of said pavement to permit the formation of a moisture barrier of solid concrete extending between the upper and lower courses but of insufficient thickness to prevent a general splitting of the monolith along the plane of said layer.

8. The process of constructing a monolithic concrete slab or the like having a substantially watertight stratum therein along which the monolith may be cleft or split, which comprises placing a course of concrete, covering slightly less than the total exposed surface of said course with a fabricated medium pervious to mortar but substantially impervious to coarse aggregate, and placing a second course of concrete over and around the edges of said medium before the setting of the first course.

9. The process of constructing a monolithic slab or the like having a substantially waterproof stratum therein along which the monolith may be cleft or split, which comprises placing a course of concrete, working the same to produce a mortar surface thereon, covering slightly less than the total exposed surface of said course with a fabricated medium pervious to mortar but substantially impervious to coarse aggregate, and thereafter placing a second course of concrete over and around the edges of said medium before the setting of the first course.
